TOY GUN RACK

Ferby G. Gaither, Statesville, N.C.

Application June 18, 1956, Serial No. 41,953

Term of patent 14 years

(Cl. D34—15)

Figure 1 is a front perspective view of a toy gun rack showing my new design; and

Figure 2 is a rear perspective view thereof.

The broken lines shown in Figure 1 are for illustrative purposes only.

I claim:

The ornamental design for a toy gun rack, substantially as shown and described.
